(57) **CLAIM**

The ornamental design for a bike trailer as shown and described.

DESCRIPTION

FIG. 1 is a front isometric view of a bike trailer showing the claimed design;

FIG. 2 is a rear isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the figures show portions of the bike trailer that form no part of the claimed design.

The shade lines in the figures show contour and not surface ornamentation.
